UNITED STATES PATENT OFFICE.

BENJAMIN F. HUTCHES, JR., OF RIDGEWOOD, NEW JERSEY, ASSIGNOR TO THE AUTOMULTI-
GRAPH CO., OF NEW YORK, N. Y., A CORPORATION OF NEW YORK.

TYPE-WRITER OPERATOR.

No. 888,807.

Specification of Letters Patent. Patented May 26, 1908.

Application filed May 2, 1907. Serial No. 371,421.

To all whom it may concern:

Be it known that I, BENJAMIN F. HUTCHES, Jr., a citizen of the United States, residing at Ridgewood, Bergen county, State of New Jersey, have invented new and useful Improvements in Type-Writer Operators, of which the following is a specification.

This invention relates to a type-writer operator which is adapted to so actuate a type-writer that the latter performs its usual functions automatically, and in addition thereto receives new sheets of paper upon the completion of the writings.

The operator is so constructed that it may be actuated either by hand or by a perforated record, which is produced automatically when the operator is worked manually.

After a record has once been formed, it is therefore possible to automatically multiply the writing to an unlimited extent, by running the record repeatedly through the operator. Each of the writings thus produced, will have the appearance and value of an original, being produced by the direct contact of the type with the paper. The operator is provided with a key-board which corresponds substantially to that of the type writer to be operated. The construction is such that the depression of a key on the operator causes the descent of the corresponding key on the type-writer, to form a writing and to simultaneously punch a record. When the latter is subsequently run through the operator, it will automatically operate the corresponding key of the type-writer, to produce the writing desired!

In addition to the usual corresponding keys of a type-writer which operate the characters, the spacing, and the carriage-shift, two further keys are provided, one of which effects the carriage-return, while the other actuates a mechanism for feeding a new sheet of paper into the type-writer, whenever desired. It will thus be seen that the operator will, with an endless record, produce any desired multiplication of circulars, letters, &c., without requiring any attendance after having once been set and started. In this way the expense of multiplying the writing is considerably reduced, each reproduction being moreover an original, and a true duplicate of the writing multiplied.

In the accompanying drawings: Figure 1 is a longitudinal section of my improved type-writer operator; Fig. 2 a plan, partly

broken away, of the key-board; Fig. 3 a left hand side view, partly in section, of the key board, showing also the automatic record-feeding means; Fig. 4 a right hand side view thereof, showing the manual record-feeding means; Fig. 5 a detail of part of the grooved record-roller; Fig. 6 a bottom view of the lower casing and inclosed parts; Fig. 7 a cross section through the casing, showing the slide and co-operating parts; Fig. 8 a detail of the mechanism for stopping the return movement of the carriage; Fig. 9 a cross section on line 9—9, Fig. 8; Fig. 10 a cross section of the operator, showing part of the mechanism for returning the carriage and feeding the paper; Fig. 11 a section on line 11—11, Fig. 10; Fig. 12 a plan of part of a record, and Fig. 13 a diagram showing the electric connections.

The numeral 15 indicates the casing of my improved type-writer operator, the top plate 16 of which is adapted to support the type-writer 17 to be actuated. In front of the latter, there is mounted upon plate 16 a hollow block or frame 18, to lugs 19 of which a transverse rod 20 is secured. To the latter are fulcrumed keys 21, 21—22, 23, 24, of which keys 21 are the usual character,—carriage-shift-and-spacing-keys, adapted to actuate the corresponding keys of the type-writer 17. Of the additional keys 22, 23 and 24, key 22 is used for returning the carriage, key 23 for feeding the writing paper, and key 24 for writing double letters. It may here be stated that the key-board of the type-writer operator must correspond substantially to that of the type-writer to be actuated, and consequently a different arrangement and number of keys is required for each different construction of type-writer.

Each key 21—24 rests upon a plunger 25 passing through the top of block 18 and pressed upwardly by a spring 26 engaging head 27 of the plunger. The upward play of the keys is limited by a cross-bar 28. The lower ends of plungers 25 constitute punches for perforating a record in manner herein-after described. Beneath each key, (excepting the double letter key 24,) there is secured to block 18 a spring contact 29 insulated therefrom as at 30. The rear downwardly bent end of each contact 29 is attached to a contact-piece 31 insulated from block 18 as at 32. From each contact 29 leads a wire 33 to an electro-magnet 34, which,

in turn, is connected by wires 35, 36 to the negative pole of a source of electricity, while block 18 is, by wires 37, 38, connected to the positive pole of such source.

Electro-magnets 34 are secured to cross-bars 39, extending between the end plates 40 of the operator-frame. Electro-magnets 34 are set in rows that correspond in number and arrangement to the number and arrangement of the rows of keys on the type-writer to be operated. Each electro-magnet has an armature 41 pivoted at 42, and carrying at its rear free end a roller 43. These rollers constitute the means for actuating the type-writer keys and consequently the type-bars of the type-writer.

As thus far described, the operation is as follows: The depression of one of the keys 21, will effect its engagement with the corresponding contact 29, to close a circuit, the current flowing as follows: from source of electricity through wires 38, 37, key 21, contact 29, wire 33, electro-magnet 34 and wires 35, 36 back to such source. The current will thus energize electro-magnet 34, which, by attracting armature 41, will lower roller 43, to depress the key of the type-writer upon which it rests. A spring-contact 29, and an electro-magnet 34 being provided for each key 21, it is obvious that the depression of any one of such keys will effect a descent of the corresponding key or spacing bar of the type-writer. The depression of any of the keys 21, will, besides closing the circuit above traced, serve to feed and perforate a record-sheet 44, in the following manner: Record-sheet 44 passes first underneath a record feed-roller 45, then partly around a grooved roller 46, and finally back over feed-roller 45, the rollers 45, 46 being journaled in block 18. Above roller 45 is arranged a rubber-covered pressure roller 47, which causes the record to be positively taken along by roller 45. For operating the latter, there is provided a swinging cross-bar 48 hung in a pair of levers 49, and arranged directly beneath the keys of the operator. Bar 48 is pressed upward against the keys by springs 50 engaging levers 49. To one of such levers is pivoted a pawl 51 that engages a ratchet wheel 52 fast on shaft 53 of roller 45. It will be seen that by depressing one of the keys 21, 22, 23, 24, the punch 25 located beneath the depressed key, will be lowered to form a perforation in record 44. Furthermore, cross-bar 48 will be lowered by said depression of the key, to correspondingly lower pawl 51 and cause the same to glide into engagement with the next tooth of ratchet 52. Upon the release of the depressed key, springs 50 will cause bar 48 to follow the upward movement of the key, and to thereby rotate feed-roller 45, and advance the record.

The means for returning the carriage at the end of each line written, are as follows: Be-

low carriage-return-key 22 is mounted a contact-spring 54, connected by wire 55 to a contact-piece 56. To the latter is secured a contact-spring 57 that rests against one arm 58 of a double lever 58, 59, fulcrumed at 60. Arm 58 normally engages a contact-piece 61, which, by wire 62, is connected to an electro-magnet 63, that, in turn, is connected by wire 64 to wire 36. Key 22 is by wire 65 connected to wire 38. Opposite electro-magnet 63, is arranged an armature 66 pivoted at 67 and influenced by a spring 68. Armature 66 is adapted to close a clutch and to thereby actuate the carriage-return means in manner hereinafter described. Within casing 15 is arranged a shaft 69 that receives rotation from an electro-motor 70. Upon shaft 69 is mounted a worm 71 that engages worm-wheel 72 turning on a vertical spindle 73 and having one or more pins 74, to constitute a clutch-member. Upon spindle 73 is slidably mounted a pinion 75 having one or more pins 76 adapted to engage pins 74, and thus constituting the second clutch-member. The hub of pinion 75 has a circumferential groove which is engaged by the free end of armature 66. It will thus be seen that pinion 75 is normally at rest, while, as soon as electro-magnet 63 is energized, the pinion will be lowered to bring pins 76 into engagement with pins 74, and thereby rotate pinion 75. The rotation of the latter is transmitted to the type-writer carriage 77, in the following manner: Within casing 15 is mounted a slide 78, guided in a frame 79, by lower and upper sets of flanged rollers 80. To slide 78 is secured a rack 81 which is engaged by pinion 75. One end of slide 78 is provided with an upwardly extending arm 82 that is connected to knob 83 of the type-writer platen 84, in manner hereinafter described. Motor 70 is normally at rest when the type-writer operator is actuated manually, but when it is desired to return the carriage, the motor is started in the following manner: From contact 61, leads a wire 85 to an electro-magnet 86, which is, turn, connected to wire 36 by branch 87. Opposite magnet 86 is arranged an armature 88, pivoted at 89 and influenced by a spring 90. The free end of armature 88 rests normally against a pair of contacts 91, 92, while, when electro-magnet 86 is energized, the armature will rest against a pair of contacts 93, 94. Of these, the contact 93 is connected by branch 95 to wire 38, while contact 94 is connected by branch 96 to wire 55. Armature 88 is by wire 97, connected to one pole of motor 70, while the other pole thereof is by branch 98 connected to wire 36.

The operation for returning the carriage by manually actuating the type-writer operator, is as follows: By depressing the carriage-return-key 22, the latter will engage contact 54 to close a circuit, the current traveling from wire 38, through branch 65, 130

key 22, contact 54, wire 55, spring 57, armature 58, contact 61, wire 85, electro-magnet 86 and branch 87, to line wire 36. This current will energize electro-magnet 86, which will attract its armature 88 until the latter rests against contacts 93 and 94. In this way two additional circuits are closed, one for maintaining the armature in the attracted position after key 22 has been released, and another for operating motor 70. In the first circuit, the current flows from line wire 38, through branch 95, contact 93, armature 88, contact 94, and branch 96, to spring 57, thus forming a shunt to the current flowing through key 22. After key 22 has been released, armature 88 will remain attracted by the current traveling through wire 95. The current for operating motor 70, travels as follows: from wire 38, through branch 95, armature 88, wire 97, electro-motor 70, and wire 98, to line wire 36. It will thus be seen that as long as armature 88 is attracted, motor 70 will remain in motion. By depressing key 22, not only is the motor started and maintained in motion, but simultaneously the carriage-return-clutch is closed by another circuit, the current of which travels as follows: from line wire 38, through branch 65, key 22, contact 54, wire 55, spring 57, armature 58, contact 61, wire 62, electro-magnet 63, and branch 64, to line wire 36. Electro-magnet 63 being thus energized, will attract armature 66, to bring pin 76 of pinion 75 into engagement with pin 74 of worm wheel 72. In this way pinion 75 is rotated to correspondingly move the carriage 77 by the engagement of pinion 75 with rack 81 of slide 78.

In order to stop the motor 70 and to open the carriage-return-clutch, after the carriage has been returned to its initial position, the following construction has been devised: Slide 78 has an eye 99, into which is tapped a screw 100. The latter is arranged in the path of arm 59 of double lever 58, 59, and is further so adjusted that it will bear against arm 59 when the carriage is about to finish its return movement. By the construction described, lever 58, 59, will be slightly turned on its fulcrum 60, so that arm 58 becomes disengaged from contact 61, and all circuits previously established will be broken. In this way armature 88 will be released to stop motor 70, and the carriage-return-clutch will be opened. Lever 58, 59, will be maintained in its tilted position for a certain length of time against the action of contact-spring 57, by engaging the hook 101 of a spring 102. During the forward run of the slide, spring 102 will be depressed by a pin or projection 103 of the advancing slide 87, so that the hook 101 becomes disengaged from arm 59 and permits spring 57 to close arm 58 against contact 61.

It will be readily understood that when

the typewriter operator is actuated manually, the depression of any one of the keys for characters, capital letters or spacing, will punch a corresponding perforation into the record 44, and will simultaneously effect a descent of the corresponding key of the typewriter. So also, the depression of the carriage-return-key on the operator, will perforate the record and cause the type-writer carriage to return to its initial position for beginning a new line. In the example illustrated, it is assumed that a type-writer is used which is so constructed that the platen for feeding the paper, is turned automatically for one or more line spaces whenever the carriage arrives at its terminal position. If type-writers of other systems are used, various means may be provided for advancing the paper without departing from the spirit of the invention.

The construction of those parts of the operator which serve to actuate the typewriter automatically by the previously formed record, is as follows: A switch-lever 104 serves to close a circuit for running motor 70 continuously as long as the operator is actuated by the perforated record. This lever is connected by branch 105 to line wire 38, and is adapted to engage a number of contacts 106 connected to a resistance 107, so that the speed of motor 70 may be readily regulated. Resistance 107 is by wire 108, connected to contact 92. Lever 104 serves, besides starting motor 70, also to close the record-feed-clutch, for which purpose contact 91 is by wire 109, connected to an electro-magnet 110, which, in turn, is connected by a branch 111, to line wire 36. Electro-magnet 110 is provided with an armature 112 pivoted at 113 and engaging with its free end, one clutch-member 114 slidably mounted upon a spindle 115 and connected thereto by groove and feather connection. Upon spindle 115 is loosely mounted a worm-wheel 116, engaging a worm 117 fast on power-shaft 69. Spindle 115 is, near its upper end, provided with a worm 118 engaging a worm-wheel 119 loosely mounted on shaft 120 of record-feed-roller 45. To worm-wheel 119 is fulcrumed a spring - influenced pawl 121 engaging a ratchet-wheel 122 fast on shaft 120. It will be seen that as soon as lever 104 is turned to engage one of the contacts 106, two circuits will be closed, the first of which starts motor 70, while the second closes the record-feed-clutch, so that the rotating shaft 69 will also rotate the record-feed-roller 45, the current traveling as follows: from line wire 38, through branch 105, lever 106, resistance 107, wire 108, contact 92, armature 88, wire 97, electro-motor 70, and branch 98, to line wire 36. In this way shaft 69 will receive continuous rotary motion from motor 70. In the second circuit closed by switch 104, the current travels from armature 88 through 130

contact 91, wire 109, electro-magnet 110, and branch 111, to line wire 36, to thereby close clutch 116, 114, and transmit rotary motion from shaft 69, to record-feed-roller 45.

5 In order to automatically operate the type-writer keys from the advancing record 44, there is provided below each key, (excepting the double-letter-key, which is hereinafter described), a contact lever 123, 10 pivoted to block 18, as at 124. Each lever 123 has a contact 125, and a downwardly extending finger 126. Fingers 126 are located above grooved roller 46, while contact 125 is located above a contact-screw 127, 15 tapped into contact-piece 31. The circumferential grooves 128 of roller 46, are in vertical alinement with the keys of the operator and also with the rows of perforations 129 corresponding to such keys. The parts are 20 so assembled that when an imperforate portion of record 44 passes beneath finger 126, lever 123 will be maintained in the raised position shown in Fig. 1, so that contact 125 is out of engagement with screw 127. As 25 soon as a perforation 129 arrives beneath finger 126, the latter will pass through such perforation to enter into alined groove 128 of roller 46. In this way lever 123 will be lowered by gravity until contact 125 rests 30 upon screw 127, to close a circuit, the current of which travels as follows: from line wire 38, through branch 37, lever 21, metallic connection 130, lever 123, screw 127, wire 33, electro-magnet 34, and branch 35, to 35 line wire 36. Electro-magnet 34, being thus energized, will attract armature 41 which operates the type-writer key in manner described. The automatic operation of the carriage-return is effected in like manner, 40 the connection 65, 22, 54, 55, used when the operator is actuated manually, being replaced by connection 65, 22, 130, 123, 55, when the type-writer operator is actuated automatically. The arrangement is such 45 that the record 44 is automatically arrested during the carriage-return motion and that it is automatically re-started as soon as the carriage has arrived at its initial position. Upon the descent of lever 123 of the carriage- 50 return-key, the current travels from wire 55, through spring 57, lever 58, contact 61, wire 85, electro-magnet 86, and branch 87, to line wire 36. By thus energizing electro-magnet 86, armature 88 will be attracted. 55 This movement of armature 88 will not effect electro-motor 70, as the latter now receives current through parts 95, 93, 88 and 97. But as armature 88 is now out of engagement with contact 91, the current is shut off 60 from electro-magnet 110, so that the record-feed-clutch will be opened and the record arrested. The parts will be maintained in the position described until the carriage arrives at its initial position, when it will tilt lever 65 58, 59, to break contact between arm 58 and

contact 61. In this way electro-magnet 86 will be deenergized, and its armature released. As parts 88 and 91 are now again in contact, magnet 110 will be reenergized to close the record-feed-clutch and advance 70 the record correspondingly.

The record for operating the machine is so made that its length is reduced to a minimum, by avoiding all longitudinal spacing between successive perforations, excepting 75 with those perforations that operate double letters and the carriage-shift. For this purpose each partial turn of ratchet 52, is so proportioned to the diameter of punch 25, that after a perforation has been made, the 80 record is fed for a length equal to the diameter of the perforation. Thus the rear edge of one perforation 129, (Fig. 12), is in tangential alinement with the front edge of the next perforation, the tangent extending at 85 right angles to the feed of the record. As this construction is only possible when different letters follow one another, I provide a special double-letter-key 24, which is used 90 when a double letter is to be written. This key has no electric connection whatever, but is simply designed, when depressed, to operate pawl 51 and thereby advance the record for a length equal to the diameter of one perforation. If a double letter is to be written, 95 the corresponding key 21 of the operator is depressed to form a perforation in the record. Then key 24 is depressed, to advance record 44 without making any perforation, and finally the same key 21 is depressed for the 100 second time. In this way the spacing necessary between the perforations of the double letter is obtained.

It will be seen from Fig. 12, that the perforation 131, produced by the carriage-shift-key is of larger diameter than all the others. In this way finger 126 of the lever arranged below the carriage-shift-key will enter its perforation in the record in advance of the finger 126 arranged below the character key. Thus 110 the carriage will be shifted before the key strikes the paper and will be held in this position until the character has been properly printed. To permit the return movement of the carriage without interfering with the 115 printing of the next letter, the double-letter-key is used to provide a blank space following the carriage-shift-perforation, as shown in Fig. 12.

The means for automatically feeding a new 120 sheet of paper to the type-writer-platen 84, after the writing on the old sheet has been completed, are as follows: In carriage 77 is mounted a feed-roller 132 which is arranged parallel and in proximity to platen 84. 125 Roller 132 is rotated from the latter by frictional contact, the platen receiving motion in manner hereinafter described. This frictional contact may be increased by providing roller 132 with a covering 133 of rubber or 130

other resilient material. Above roller 132 there is secured to carriage 77, by brackets 134, a magazine 135 containing a stack of blank sheets 136. Magazine 135 is composed of an inclined bottom 137, side walls 138, 139, and front and rear walls 140, 141. The magazine is so arranged that the edge formed between bottom 137 and front wall 140, is located vertically above the axis of roller 134. Along such edge I provide bottom 137 with a longitudinal slot 142, while a guard 143, curved concentrically to roller 132, extends forward from wall 140 and partially around roller 132. The parts are so assembled that a small passage remains between roller 132 and guard 143, of a height to accommodate a single sheet 136. The bottom sheet contained in magazine 135 rests with its front portion upon roller 132, and the sheet will thus be taken along by such roller, upon the rotation of the latter. From roller 132 the sheet is wound partly upon platen 84, to which it is held by bands 144, or other suitable means. To set the magazine to sheets of different widths, it is provided with a movable transverse partition 145, adjustable by screws 146.

Upon the completion of a writing, a turn is given to platen 84, by the means hereinafter described, for the purpose of ejecting the old sheet and introducing a new sheet. These means are as follows: In slide 78 is rotatably mounted an elongated toothed wheel or pinion wire 147, which is engaged by a pinion 148. The latter is fast on a spindle 149 which turns in a fixed bearing 150. At the opposite side of bearing 150, there is mounted on spindle 149, a beveled gear wheel 151 adapted to engage a similar wheel 152 fast on a vertical spindle 153. Gear wheel 152 is normally held out of engagement with wheel 153 by a spring 154 interposed between pinion 148 and bearing 150. The inner end of spindle 149 is engaged by one arm 155 of a bell crank lever fulcrumed at 156. The other arm 157 of this lever constitutes the armature of an electro-magnet 158.

As thus far described, it will be seen that when electromagnet 158 is energized in manner hereinafter described, it will attract armature 157 to swing arm 155 outwardly and thereby bring beveled gear wheel 151 into operative engagement with wheel 152, so that rotary movement is imparted from power-shaft 69 to pinion wire 147 by gear wheels 152, 151, spindle 149 and pinion 148. This rotary movement is imparted to feed-roller 132 in the following manner: Within upright arm 82 is rotatably mounted a spindle 159 intergeared with pinion wire 147 by bevel wheels 160, 161. Spindle 159 in turn is intergeared by wheels 162, 163, with a horizontal spindle 164 rotatably mounted in bearing 165 of arm 82. To spindle 164 is secured a ratchet-wheel 166 engaged by a resili-

ent finger 167 which is fastened to a perforated head 168 loosely mounted upon spindle 164. The enlarged end 169 of head 168 is provided with a recess 170 adapted to receive the usual knob or handle 83 of platen 84, which is secured to the head by clamp-screws 171. In this way the slide 78 is connected to platen 84 and consequently to carriage 77, so as to be taken along by the same during the writing operation, while the carriage is taken along by the slide during the carriage-return motion. It will further be seen that as soon as beveled wheels 151, 152, are brought into engagement, the rotation of power-shaft 69 will be transmitted to platen 84 by transmission 152, 151, 149, 148, 147, 160, 161, 159, 162, 163, 165, 166, 167 and 168. The ratchet connection between head 168 and spindle 164 permits the platen 84 to be rotated independently from the above described mechanism at the commencement of each new line of the writing. As the length of the paper to be fed into the type-writer may vary, means are provided which permit the rotation of pinion wire 147 and consequently of platen 84 for any desired length of time. These means are operated by the paper-feed-key 23, or its coöperating lever 123, in such a manner that a first descent of the key or lever will start the movement of the paper-feed-device, while a second descent of the key or lever will stop such movement. The time that elapses between the above two descents corresponds to the extent to which the paper is to be fed forward.

The means hereinabove referred to are as follows: Contact-spring 172 of the paper-feed-key 23 is by wire 173 connected to an electro-magnet 174, which, in turn, is by branch 175 connected to a wire 176 leading to line wire 36. Opposite electro-magnet 174 is arranged an armature 177 fulcrumed at 178. To the free end of armature 177 is pivoted a spring-influenced pawl 179 that engages a ratchet-wheel 180 having conducting teeth 181, alternating with non-conducting teeth 182. Opposite pawl 179, ratchet-wheel 180 is engaged by a contact 183 which is by wire 184 connected to the electro-magnet 185 opposite which armature 157, hereinabove referred to, is arranged. Electro-magnet 185 is by wire 176 connected to line wire 36, while armature 177 of electro-magnet 174 is by wire 186 connected to line wire 38.

In Fig. 13, the parts are shown in the position when the paper-feed-mechanism is at rest. When the paper-feed-key 23 is depressed, (or when finger 126 of lever 123 arranged below key 23 enters a hole in the record 44), a circuit is closed, the current traveling as follows: from line wire 38, through branch 187, key 23, (or lever 123), wire 173, electro-magnet 174, and wires 175, 176, to line wire 36. In this way electro-magnet 130

174 will attract armature 177 to rotate ratchet-wheel 180 for the length of one tooth. After the release of key 23, electro-magnet 174 is deenergized, so that armature 177 will be retracted and pawl 179 will engage the next conducting tooth 181 of ratchet-wheel 180. By the rotations of wheel 180, pawl 179 and contact 183 will come into engagement with the conducting parts of the ratchet, so that a current will flow as follows: from line wire 38, through branch 186, armature 177, pawl 179, ratchet-wheel 180, contact 183, wire 184, electro-magnet 185, and wire 176, to line wire 36. Electro-magnet 185 will thus attract armature 157, to thereby effect an engagement of gear-wheels 151, and 152. In this way platen 84 will be rotated until key 23 is depressed for a second time, or its coöperating lever 123 is lowered by engaging a perforation of record 44. Thus a second impulse is imparted to electro-magnet 174, and armature 177 will be attracted to rotate ratchet-wheel 180 for the distance of another tooth, to bring non-conducting teeth 182 into engagement with pawl 179 and contact 183. In this way the circuit is broken, electro-magnet 185 is deenergized, and spring 154 permitted to bring wheels 151, 152, out of engagement, so that the rotation of platen 84 is discontinued. If the mechanism for feeding a sheet of paper into the type-writer is actuated by key 23, switch 104, must be closed to start electro-motor 70, while a switch 188, provided within the circuit for the record-feed-clutch, must be opened.

It will be seen that my improved operator produces an original print of the writing, and simultaneously a record of such print. If it is desired to duplicate such original, the record, (which should be made endless), is fed continuously through the operator, the desired number of times. After the completion of each sheet of writing, the latter is automatically ejected and a new sheet is introduced, whereupon the operator is automatically restarted. The writings thus produced are not the carbon copies, heretofore made, but are all originals, *i. e.*, they are all formed by a direct contact of the type with the paper. In this way an unlimited number of type-written duplicates of a writing can be automatically turned out, without requiring the services of an attendant.

55 I claim:

1. In a type-writer operator, a power-shaft, and key-controlled means for operatively connecting said shaft to carriage-return means and to means for feeding a sheet of paper to the type-writer platen, substantially as specified.

2. In a type-writer operator, a power-shaft, key-controlled means for operatively connecting said shaft to carriage-return means and to means for feeding a sheet of

paper to the type-writer platen, combined with means for manually actuating the keys of a type-writer, substantially as specified.

3. In a type-writer operator, a power-shaft, key-controlled means for operatively connecting said shaft to carriage return means and to means for feeding a sheet of paper to the type-writer platen, combined with means for manually actuating the keys of a type-writer, and means for simultaneously producing a record, substantially as specified. 75

4. In a type-writer operator, a power-shaft, automatic means for operatively connecting said shaft to carriage-return means 80 and to means for feeding a sheet of paper to the type-writer platen, combined with automatic means for actuating the keys of a type-writer, substantially as specified.

5. In a type-writer operator, a power-shaft, a record, first means controlled by the record for operatively connecting said shaft to carriage-return means, second means controlled by the record for operatively connecting the shaft to means for feeding a sheet 90 of paper to the type-writer platen, and third means controlled by the record for operating the keys of a type-writer, substantially as specified.

6. In a type-writer operator, a power-shaft, key-controlled means for operatively connecting said shaft to carriage-return means and to means for feeding a sheet of paper to the type-writer platen, combined with keys for actuating the type-writer 100 characters, and means actuated by the keys for producing a record, substantially as specified. 95

7. In a type-writer operator, a power-shaft, a character key, a carriage-return key, 105 a paper feed key, means controlled by the character key for operating the corresponding key of a type-writer, means controlled by the carriage-return key for operatively connecting the power-shaft to carriage-return means, and means controlled by the paper feed key for operatively connecting said shaft to means for feeding a sheet of paper to the type-writer platen, substantially as specified. 110

8. In a type-writer operator, a power-shaft, a character key, a carriage-return key, 115 a paper feed key, means controlled by the character key for operating the corresponding key of a type-writer, means controlled by the carriage-return key for operatively connecting the power-shaft to carriage-return means, means controlled by the paper feed key for operatively connecting said shaft to means for feeding a sheet of paper to the type-writer platen, and means actuated by 120 the keys for producing a record, substantially as specified.

9. In a type-writer operator, a power-shaft, a slide engaging a type-writer carriage, a coupling between shaft and slide, a 130

- carriage-return key, and means controlled by said key for closing the coupling, substantially as specified. 1
10. In a type-writer operator, a power-
5 shaft, a slide engaging a type-writer carriage, a coupling between shaft and slide, and means controlled by the slide for opening the coupling, substantially as specified. 60
11. In a type-writer operator, a power-
10 shaft, a slide engaging a type-writer carriage, a coupling between shaft and slide, a carriage-
return key, means controlled by said key for closing the coupling, and means controlled
15 by the slide for opening said coupling, substantially as specified. 65
12. In a type-writer operator, a power-
shaft, a slide engaging a type-writer carriage, a coupling between shaft and slide, a record, and means controlled by the record for
20 closing the coupling, substantially as specified. 70
13. In a type-writer operator, a power-
shaft, a slide engaging a type-writer carriage, a coupling between shaft and slide, a record,
25 means controlled by the record for closing the coupling, and means controlled by the slide for opening said coupling, substantially as specified. 75
14. In a type-writer operator, a power-
30 shaft, a slide engaging a type-writer platen, a carriage-return key, a paper feed key, means controlled by the carriage-return key for transmitting longitudinal movement from the power-shaft to the slide, means controlled
35 by the slide for arresting said movement, and means controlled by the paper feed key for transmitting rotary movement from the power-shaft to the platen, substantially as specified. 80
- 40 15. In a type-writer operator, a power-
shaft, a slide engaging a type-writer platen, a record, means controlled by the record for transmitting longitudinal movement from the power-shaft to the slide, means controlled
45 by the slide for arresting said movement, and means controlled by the record for transmitting rotary movement from the power-shaft to the platen, substantially as specified. 85
16. In a type-writer operator, a record, a
50 contact-lever engaging the same, a first electro-magnet in circuit with the contact-lever, an armature controlled by said first electro-magnet, a pawl pivoted to the armature, a ratchet wheel having alternating conductive and non-conducting teeth engaged
55 by the pawl, a second electro-magnet in circuit with the ratchet wheel, and means controlled by the second electro-magnet for rotating a type-writer platen, substantially as specified. 90
17. In a type-writer operator, a carriage-
return-key and a type-writer carriage, combined with a spring-influenced lever, a first electro-magnet and a second electro-magnet in circuit with the key and lever, an electro-
motor controlled by the first electro-magnet, and a clutch controlled by the second electro-
magnet and adapted to transmit motion from the electro-motor to the carriage, substantially as specified. 95
18. In a type-writer operator, a paper-
feed-key, a type-writer platen, means controlled by a first depression of the key for rotating the platen, and means controlled by a second depression of the key for arresting the platen, substantially as specified. 100
19. In a type-writer operator, a paper-
feed-key, combined with a type-writer platen, a first electro-magnet in circuit with the key, a second electro-magnet, means controlled by the first electro-magnet for energizing and deenergizing the second electro-magnet, and means controlled by the second electro-magnet for rotating the platen, substantially as specified. 105
20. In a type-writer operator, a record, a contact-lever engaging the same, a first electro-magnet in circuit with the lever, a second electro-magnet, a record-feed-clutch controlled by the second electro-magnet, and means controlled by the first electro-magnet for energizing and deenergizing the second electro-magnet, substantially as specified. 110
21. In a type-writer operator, a record, a contact lever engaging the same, a first electro-magnet in circuit with the lever, a second electro-magnet, means controlled by the first electro-magnet for energizing and deenergizing the second electro-magnet, and means controlled by the second electro-magnet for rotating the platen, substantially as specified. 115

Signed by me at New York city, (Manhattan,) N. Y., this 1st day of May 1907.
